[57] CLAIM

The ornamental design for a wax dispensing buffer, as shown and described.

DESCRIPTION

FIG. 1 is a perspective view of a wax dispensing buffer showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The electric cord is shown broken away in FIGS. 1 and 4-7 for ease of illustration and is understood to represent indeterminate length.

FIG. 2.

FIG. 4.

FIG. 3.

FIG. 5.
